UNITED STATES PATENT OFFICE.

WILLIAM P. BETTENDORF, OF DAVENPORT, IOWA.

DESIGN FOR A ROLLED-METAL BEAM.

SPECIFICATION forming part of Design No. 29,546, dated October 25, 1898.

Application filed August 12, 1898. Serial No. 688,457. Term of patent 14 years.

To all whom it may concern:

Be it known that I, WILLIAM P. BETTENDORF, a citizen of the United States, residing at Davenport, in the county of Scott and State of Iowa, have invented and produced a new and original Design for Rolled-Metal Beams, of which the following is a specification, reference being had to the accompanying drawings, forming part thereof.

10 In the drawings, Figure 1 is a perspective view of a rolled-metal beam made according to my design. Fig. 2 is an end view of the same.

In the drawings, A represents a rolled-metal 15 plate of sufficient width having its longitudinal side portions B correspondingly bent downward at right angles thereto to form corresponding side flanges B B and convert the

same into a channel-iron. This plate is provided on its upper surface or on the side of the plate opposite that from which flanges B B project with longitudinal parallel corresponding ridges C C, which are located an equal distance from the center of width of the plate A and have their sides farthest from said center of width made flat and at right angles to the sides of said plate.

Having described my invention, what I claim as new, and desire to secure by Letters Patent, is—

20 The design for a rolled-metal beam as herein shown and described.

25 WILLIAM P. BETTENDORF.
